UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

CASTING APPARATUS.

1,357,343.

Specification of Letters Patent.

Patented Nov. 2, 1920.

Application filed June 1, 1917. Serial No. 172,193.

To all whom it may concern:

Be it known that I, EMIL E. NOVOTNY, a citizen of the United States, residing at Riverside, in the county of Cook and State of Illinois, have invented new and useful Improvements in Casting Apparatus, of which the following is a specification.

This invention relates to casting boxes or molding apparatus through the agency of which an article may be rapidly, conveniently and economically molded or cast under heat and pressure.

In the present instance I have shown my invention as particularly adapted for the casting or molding of matrices and printing plates made therefrom but I wish it to be understood that this is merely by way of illustration, as the invention is not limited in its useful application to this particular purpose, but may be employed for the molding or casting of other articles, or employed in any connection wherein its use as a molding apparatus may be found desirable or advantageous. Where I have herein used the term casting box I wish it to be understood in its broad acceptation as including an apparatus or structure wherein articles may be molded, formed, shaped or cast.

One of the objects of the present invention is the provision of a casting box wherein the means employed for heating purposes are so located as to provide an efficient heating zone relatively near to the article being molded or cast, so that not only is there economy in heat application to such article, but the latter through the medium of the heat so applied may be rapidly brought to a state suitable for molding under pressure, thus increasing the per diem production of the apparatus by lessening the time necessary to mold the individual article.

It is also my purpose to provide a casting box wherein a cooling agent such as water may be conveniently employed for the purpose of cooling the article after it has been molded under heat and pressure. This cooling agent is applied in such manner that the casting box may be rapidly cooled, inasmuch as there is no great bulk of metal between the cooling agent ad-

mitted to the press platens and the pressing faces of such platens, as is commonly the case with the ordinary water-cooled press. Thus I obviate the expense and delay incident to waiting for the press to cool, and I also avoid the employment of separate cooling apparatus which is sometimes used in preference to wasting time while waiting for articles to cool in the ordinary water-cooled press.

It is also my purpose to provide a casting box wherein provision is made for electrically heating the platens or press surfaces of the same, the arrangement being such that these platens may be readily heated to the necessary temperature to insure the accurate molding or casting of the article.

Furthermore, it is my purpose to provide a casting box which is so constructed that in the process of its manufacture the necessity of a great amount of boring, drilling and grinding and machining the same, or portions thereof, is avoided, as in some cases the box is in the nature of a molded or cast structure, reinforced by suitable strengthening elements embedded in the body of the box during manufacture, at which latter time the heating and cooling elements may also be placed in position, provision being made for removing the electrical heating devices when desired.

Another object of the invention is the inclusion in the body structure of the box certain elements which tend to increase the heat conductivity or heat application of the box.

I also aim to provide a casting box which will embody the desired features of simplicity, efficiency, strength and durability and which is capable of being employed for the accurate and economical molding of the articles for which it is adapted.

With the above recited objects and others of a similar nature in view my invention consists in the construction, combination and arrangement of parts set forth in and falling within the scope of the appended claims.

In the accompanying drawings,

Figure 1 is a vertical cross sectional view taken through a preferred form of casting

box embodying my invention and illustrating the plate and its matrix in molding position therein.

Fig. 2 is a top plan view of the bed section of the casting box shown in Fig. 1, with the matrix-supporting bed plate omitted to show the construction and location of the electric heating element in this lower section.

10 Fig. 3 is a cross sectional view taken on the line 3—3 of Fig. 2.

Fig. 4 is a cross sectional view taken through a modified form of casting box, in this case the box sections being composed 15 of metal.

Fig. 5 is an end view of the top section of the casting box shown in Fig. 4.

Fig. 6 is a top plan view thereof.

Fig. 7 is a view similar to that of Fig. 20 4, of another modified form of casting box.

Fig. 8 is an end view of the upper section of the casting box shown in Fig. 5.

Fig. 9 is a plan view of such upper section.

25 Fig. 10 is a cross sectional view taken through another form of casting box and showing a modified manner of cooling the box sections.

Fig. 11 is an end view of the lower section of the casting box shown in Fig. 10.

30 Fig. 12 is a top plan view of the lower section of the casting box of Fig. 10.

Fig. 13 is a cross sectional view of a modified form of casting box adapted particularly for the casting of semi-cylindrical or 35 curved articles.

Fig. 14 is a plan view of the casting box shown in Fig. 13.

Referring now to the accompanying drawings in detail, and particularly to the form 40 of casting box shown in Figs. 1 to 3 inclusive, the letter A indicates the top or cover section of the casting box while the bottom or bed section thereof is shown at B. As 45 will be seen by reference to Fig. 1, the matrix M may be clamped on the bed of the section B by means of suitable clamping bars C, gripping the marginal edges of the matrix, and from this matrix the plate P, 50 preferably of a plastic material is intended to be molded, suitable bosses or projections p, being formed on the back of the printing plate for the purpose of obtaining registration of the plate on the press, as hereinafter 55 described, these bosses being made by the sockets e, of the core plate D, the latter being interposed between the cover and bed sections of the casting box and operating as hereinafter described. As the cover section A and the bed section B of the box are 60 similar in construction, or duplicates one of the other, a description of one will suffice. Each section comprises a molded body of hardened plastic material, such as a phenolic 65 resin, or phenolic condensation product in-

dicated by the numeral 1, and made of a desired size and shape. During the molding of this plastic body 1, there is embedded in the same parallel vertically disposed reinforcing bars 2, preferably of metal, such as steel or the like, these bars having in-turned marginal flanges for the purpose of anchoring or hooking the plastic material. Such bars may be of any suitable dimensions, preferably being of a depth nearly or approximately equal to the thickness of the body of plastic material, especially at the central field or portion of the latter. The body of plastic material 1 is cast or molded in a frame formed of angle irons 4, the inner faces of which are grooved or notched as at 5 to form small anchoring sockets for the plastic material 1. Where, as in the present case, the box section is approximately square or rectangular in 75 form, there are four of these angle irons making, if desired, a continuous frame and constituting reinforcing and strengthening border members for the block of plastic material. In the molding of the plastic material suitable core pieces are employed to mold slots or channels 6, adjacent a face of the box section. In the case of the box section B, these space slots or channels 6 are located near the top face of the section, 80 while in the case of the cover section A of the box, these channels or slots are near the bottom face of the section. The purpose of these slots is to receive or accommodate the heating bars or strips 7, of the heating element 8, as shown in Fig. 2, this heating element being in the nature of a grid, in the sense that spaced bars 7 are connected or joined to, a plate 9, which lies in the cut-away section or shoulder 10 of the plastic body 1. At the time of molding each section, a metallic plate 11 is employed, and such plate has its opposite edges grooved as at 12 to anchor the material of the body 1, as shown at 13. In addition, during the molding operation, metallic strips or plates 14, which form the bottom walls of the grooves 6, are embedded in the plastic material, the opposite longitudinal edges of these plates being grooved as at 15 for the purpose of anchoring the plates or strips in the plastic material. These strips or plates 14 will therefore contact with or support the bars of the heating element, and will also act as conductor plates for the cooling agent 100 when the casting box is being cooled as hereinafter described.

For the purpose of cooling the box I am providing suitable piping indicated at 16, this piping being bent back and forth to 125 form a coil, as shown in Fig. 2, the parallel sections of the coil being properly spaced and lying directly beneath and in contact with the conductor plates 14. Of course this cooling coil or piping is embedded in 130

the block of plastic material 1, during the molding of the latter and the water inlet of the coil is shown at 17 while the outlet is shown at 18. Thus when desired, water 5 may be admitted to the coil and, circulating therethrough, tend to cool the plates 14, and consequently the heating element contacting with the plates as hereinbefore described. The result is that as the heating element 10 may thus be rapidly cooled, and the plates 11, and the core plate D, as well as the matrix and article imposed thereon will have the temperature thereof lowered to a point to permit the separation and the removal 15 of the article being molded.

The core plate D, as shown in Fig. 1 comprises a metallic frame, embracing the body of plastic material 20, which may be of a phenolic substance if desired. In this 20 body of plastic material 20, I preferably embed small portions of metallic material 21 which may be in the nature of borings, filings, metallic granules, or the like, to increase the heat conductivity when the core 25 plate is in molding position and heat is applied thereto. The top of this core plate has also embedded or molded therein a flat metallic plate 22, which when the core plate is positioned in the casting box will lie in 30 contact with the plate 11 of the top section of the box and consequently receiving the heat from such plate 11, will rapidly and quickly conduct the same, with the assistance of the metallic granules 21, to the article such as the plate P in the box, therefore tending to quickly heat the plate material to the proper temperature for molding.

By reference to Fig. 1, it will be seen that 40 the core plate D is provided with small spaced sockets or depressions c, and as the core plate, in operation rests directly upon the plate blank being molded, when pressure is applied the material at the back of 45 the printing plate P being made will be forced into these sockets or depressions thereby forming the spaced bosses p on the back of the printing plate.

If desired, the clamping bar C may be 50 provided with knife-like edges 23, for shearing or trimming the side edges of the plate P during the molding operation, the surplus material while in its plastic state passing through the small openings 24 leading 55 to grooves or gutters 25, in the clamping bars and from which grooves or gutters the material may escape through the passages 26. This constitutes a simple arrangement for trimming the plate and removing the 60 surplus plastic material.

The electric conductors for the electric heating grid or element are shown at 27 and 28, these being merely conventionally illustrated, as the electric connections for the 65 grid or heating element may be arranged to

suit the particular conditions under which the box is to be used. It will be understood that the electric heating element itself may be of any suitable form and shape, and I have illustrated herein merely by way of 70 illustration one form of element adapted for the particular box shown and described.

Referring to Fig. 2, wherein the casting box is shown with the matrix supporting bed plate omitted, it will be seen that the 75 electric grid or heating element 8 is shown as inserted in operative position in the casting box with the arms or bars 7 of the grid lying in the slots 6 of the casting box section, these arms extending substantially 80 throughout the length of the slots or channels. This grid of course has connected therewith the electric conductors 27 and 28, and when current is switched on it passes through the grid, heating the same, as is 85 usual in appliances of this kind. In Fig. 2, the conductor 27 is indicated as a positive conductor while 28 is the negative conductor, but, of course, as above stated the electric connections to the grid or heating 90 element are simply conventionally shown. The heating element may be wired in any well known manner as is usual with electric heating coils, grids, plates and the like.

From the above description, taken in connection with the accompanying drawings, the construction and operation of the preferred form of casting box shown in Figs. 1 to 3 inclusive will be readily understood. When it is desired to mold an article, such 100 for instance as a printing plate P, the matrix M is positioned on the bed plate 11 of the lower section B of the box, and the core plate D having been properly positioned to locate the bosses p in predetermined places 105 on the back of the plate, the top section A of the casting box is closed or placed in position. Heat is now applied to the heating elements of the top and bottom sections of the casting box by closing the electric circuit or current being applied from any suitable source.

When this takes place, the plates 11 will be rapidly heated by the electric heating elements lying thereagainst and this heat 115 will be transmitted in the case of the bottom section of the casting box through the matrix to the printing plate P, and in the case of the top section of the casting box through the core plate to such plate P. Thus the 120 printing plate will be thoroughly subjected to heating action and will be rapidly reduced to a state when it may be molded, with the finest detail, against the matrix, pressure at the same time being exercised 125 by platens of a suitable press for the purpose of closing the casting box to the degree permitted by the clamping bars C, which act as bearers to limit the downward or closing movement of the core plate against the 130

plate being molded. When desired, after molding under heat and pressure, the casting box may be cooled by cutting off the current or opening the electric circuit and by admitting water through the inlet 17, to the cooling coil, the water circulating through this coil tending to rapidly cool the casting box and matrix and plate therein as previously described.

10 In the case of the casting box shown in Figs. 1 to 3 inclusive, it will be noted that it is composed of a body of plastic material reinforced and strengthened by metallic members which act in some instances as heat conductors and in some instances as heat radiating or cooling elements and furthermore it will be noted that the means for cooling the casting box and its contents are embedded in the box sections during the 20 making of the latter. Of course the electric heating element or grid may be placed in and removed from the box as desired, being merely slipped into and out of the grooves or slots 6 formed during the making of the 25 casting box sections.

In Figs. 4, 5 and 6 I have shown a slightly modified form of the invention. In this case the cover and bed sections A¹ and B¹ of the casting box are formed of cast metal, such as steel, and during the formation of these box sections cooling coils such as are shown at 29 and slots or channels 30, are molded in the box sections, the piping or cooling coil 29 being of course for the water, 35 while the slots 30 are intended to receive the heating element as described for the structure shown in Figs. 1 to 3. The core plate D¹ is also of metal and may be provided with screws 31, the shanks 32 of which will form threaded sockets in the bosses 33, molded on the back of the plate P¹ being made on the matrix M¹. Of course suitable clamping bearer bars 35 are employed between the core plate and the bottom section 40 B¹ of the box. The upper section A¹ is connected with the bottom section B¹ through the side flange 36 bolted as at 37 to the top section and having an open slot 38 at its lower end for the slotting of the bolt shank 39, threaded in the lower section of the casting box, a wing nut 40 being employed for detachably fastening the flange to the lower section of the casting box. The operation of this box is substantially the same as that 45 heretofore described.

In Figs. 7, 8 and 9 I have shown a further modified form of casting box. In this instance the upper or cover section A² and the bed or lower section B² of the box are 50 machined from blocks or plates of steel, cored out or bored to provide connecting water passages or channels 41, which extend longitudinally and transversely. Two of these channels may be connected with the 55 water inlet pipe 42 and the water outlet pipe

43 and the ends of the other bores or channels may be closed with suitable plugs as shown at 44. In this instance when the water is admitted it will circulate through the cored passageways or channels and tend to 70 rapidly cool the box sections. Each section of the box is also cored or cut to provide slots 45 for the reception of the heating element and these grooves or slots 45 are covered by heat conducting plates 46, fastened 75 in position by bolts 47. The core plate as shown at D² is similar to the core plate shown at D¹ in Fig. 4, and this casting box is likewise provided with the clamping bearer bars 48 to confine and trim the material of the plate P², resting on the matrix M². This form of casting box is also operated in a suitable hydraulic press as described for the forms of casting box heretofore mentioned.

80 In the modified form of the invention shown in Figs. 10 to 12 inclusive, the upper casting box member A³ and the lower casting box member B³, are also preferably made of machined metal, such as steel, and in this 90 instance rows of longitudinally extended spaced water channels 50 all of relatively large size are cored or cut in the body of the box sections a³ and b³. In the present instance each of these channels 50, is shown 95 as approximately rectangular in the cross section, and each of such channels at one side is cut through the face of the block of metal. The open sides of the channels thus formed, and indicated at 51, are covered or closed by packing sheets 52 of any suitable material such as asbestos or the like, and these packing sheets in turn are covered or faced with steel plates 53 fastened by bolts 54 to the blocks of metal constituting the body portions of the box sections. The inner portions 55 of each of the channels 50 terminates in the slot 56 which is adapted to receive the plate or strip of the heating element or grid and it will be 100 observed that such heating element when arranged in the slot may be brought into direct contact with the cooling agent, such as water admitted to the channels 50. The water may be admitted to these channels through an 105 inlet pipe 57 and may then pass out through an outlet pipe 58. Of course each box section is provided with an inlet pipe and outlet pipe. In order to permit all of the 110 channels of each casting box section to communicate, and thereby provide for the proper distribution of the water, transverse slots 59 are cut in the partition walls 60, separating the channels 50, and these transverse slots 59 thus provide means for permitting the water to flow from one channel to another. In this modified form of casting box a cored plate D³ is also employed for operating upon the plate P³, the matrix of such plate being shown at M³. The clamp- 115 120 125 130

ing bars C³ are also employed for confining the flow of the plate material and for limiting the closing of the casting box and trimming the edges of the plate as heretofore 5 described for other forms. The usual heating element 8 heretofore described in detail is also employed in connection with this type of casting box. It will be noted that this modified form of box composed as it is of 10 metal may be readily heated by the electric heating element 8 and may be quickly cooled inasmuch as a large area is provided for the distribution of the water in the box sections and furthermore, the water may be 15 brought directly into contact with the various sections of the heating element.

In Figs. 13 and 14 I have shown the casting box which may be used in the formation of articles, such as curved or semi- 20 cylindrical plates. This form of box is built up of plastic material suitably hardened and reinforced at desired points with appropriate substances, such as sections or pieces of metal. This form of box is also intended 25 to be electrically heated, and to be cooled by the circulation of water.

Referring to said Figs. 13 and 14, the letter A⁴ indicates the top section of the casting box which comprises a cover section 59^a of 30 plastic material reinforced by flanged metal plates 60^a, and by the vertical metal plates 61, and the horizontal plate 62. A threaded socket 63 may be formed in this section A⁴, for the purpose of bolting the same to the 35 top platen of a suitable press (not shown). The lower portion of this top section A⁴ is in the nature of a semi-cylindrical body of molded plastic material shown at 65 in which I embed the cooling coils 66, a 40 curved approximately semi-cylindrical plate 67 enveloping this plastic section 65, and resting against the pipe sections of the coils 66, the ends of this curved plate 67 being embedded as at 68 in the plastic material 45 of the cover portion. A second curved or semi-cylindrical plate 69 is arranged outside of and in spaced relation to the curved plate 67 and separated therefrom by spaced metallic ribs 70, so that slots 71 are formed

50 for the insertion of properly shaped heating element or elements. The heating element employed is in the nature of an electric grid similar to that heretofore described for the other forms of casting box except that the 55 members thereof are properly curved to permit of their insertion in the slots 71. The core plate for this curved box is shown at D⁴ and is of course semi-cylindrical in form, being provided with outturned flanges 72 60 which rest on the bearer bars 73, the latter carrying clamping strips 74, for engaging the edges of the matrix and abutting against the ends of the plate. In Fig. 13 I have not shown the matrix or plate, as these are 65 simply curved to conform to the shape of the

molding sections of the box but it will be understood that they occupy the space X, formed between the curved core plate and the curved bed plate 75 of the lower section B⁴ of the box. In addition to this bed plate 70 75 this lower section B⁴ comprises a body of plastic material shown at 76 the sides of which are reinforced and confined by vertical flange plate 77, while the bottom of the plastic body is provided with a curved metallic base plate 78. Contacting with the bottom face of the bed plate 75 is a curved metallic plate 79, embedded at its ends as at 80 in the plastic material and this plate is spaced apart from the second curved plate 80 81, by means of ribs 82 also of metal so that slots 83 are formed for the reception of the heating element or elements for the lower section of the box. Pipe sections 84 constituting the cooling coil and adapted to be 85 supplied with water, are embedded in the body of plastic material between the curved plate 83 and the metallic base plate 78. This bottom section B⁴ of the casting box is intended to rest upon the saddle E which may 90 be bolted as at 85 to the bottom platens or bed of a suitable press (not shown) and this saddle is also preferably in the nature of a body of plastic material 86, having flanged metallic side plates 87 and the metallic base 95 plate 88. The plastic material of this saddle E may further be reinforced by suitable means, such as by the metallic bars 89, embedded therein.

The operation of this form of casting box 100 is substantially the same as that described for the other forms shown herein, except that the saddle for the bottom section of the box, as well as the upper section of the box are intended to be permanently secured to the 105 bottom and top platens respectively of a suitable press. It will be noted that this type of casting box is also electrically heated by an electric heating element and is cooled by the admission of a cooling agent, such as 110 water, to the cooling coils. Of course the plate produced by this box will be semi-cylindrical as is desired for use on the form cylinder of a rotary press.

It will further be noted that I have provided casting boxes for the making of either flat or curved plates, and which boxes may be rapidly and economically heated and cooled at desired times, thereby greatly increasing the output of the apparatus and 120 consequently attaining a saving of time and labor and expense in the production of the molded articles.

While I have herein shown and described certain preferred embodiments of the invention, I wish it to be understood that I do not limit myself to all of the details of construction herein set forth by way of illustration, as modification and variation may be made without departing from the spirit 130

8
of the invention or exceeding the scope of the appended claims.

What I claim is:

1. In a casting box a pair of companion members, each including a heating section, a removable heater for each heating section and means for cooling each heating section, a clamp for holding an article upon one of such members, and a core plate interposed between the companion members.
2. A casting box including a body portion of hard and set plastic material, a metallic heater therefor comprising a plate-like heating section, a removable heating element positioned in a channel in the body portion and in contact with the plate-like heating section for heating the latter, and means for cooling the plate-like heating section.
3. A casting box comprising a body portion including a heating section composed of a metallic plate-like member, a removable electric heating grid located within the body portion in contact with the plate-like member to heat the latter, and means for cooling the plate-like member.
4. In a casting box, a body portion composed of hard and set plastic material provided with metallic reinforcements, a plate-like heating section for the body portion, said body portion having a channel therein adjacent the heating section, a removable heating element positioned in said channel in contact with the heating section, and a conducting pipe positioned in the body portion adjacent the heating element for con-

ducting a cooling fluid to and through the body portion to cool the heating section thereof.

5. In a casting box, a body portion including a heating plate forming one face of the body portion, a removable heating member located within the body portion and bearing against the plate, a strip member bearing against the opposite face of the heating member, and a pipe located within the body portion adjacent the strip and adapted to have a cooling fluid circulate therethrough for cooling purposes.

6. A casting box comprising two companion members, each comprising a body portion made from hard and set plastic material and having a heating element inserted therein and having a conduit embedded therein adjacent the heating element for the passage of a cooling fluid, and a core plate interposed between the two companion members.

7. A casting box comprising a top section and a bottom section having correspondingly curved walls, a curved core plate associated with the sections, a clamping member for clamping a curved matrix in position in the casting box, a removable electric heater for heating the casting box, and fluid conduits embedded in the casting box sections for the circulation of a cooling fluid.

In testimony whereof I have hereunto set my hand.

EMIL E. NOVOTNY.
